US00D958535S

(12) **United States Design Patent** (10) **Patent No.:** **US D958,535 S**
(45) **Date of Patent:** **** Jul. 26, 2022**

(54) **OUTER COVERING FOR EARBUD CASE**

(71) Applicant: **Speculative Product Design, LLC**, San Mateo, CA (US)

(72) Inventors: **Monica Elizabeth Wright**, Falls Church, VA (US); **Derrick Del Moral**, San Bruno, CA (US); **Bryan Lee Hynecek**, Redwood City, CA (US)

(73) Assignee: **Speculative Product Design, LLC**, San Mateo, CA (US)

(**) Term: **15 Years**

(21) Appl. No.: **29/743,050**

(22) Filed: **Jul. 17, 2020**

(51) LOC (13) Cl. **03-01**

(52) U.S. Cl.

USPC **D3/299**

(58) **Field of Classification Search**

USPC D3/207, 212, 215, 218, 219, 266, 273, D3/275, 294, 299, 300, 302, 313, 201, D3/203.1, 205, 263, 264, 265, 274

CPC H04R 2460/17; A45C 11/04

(57) **CLAIM**

The ornamental design for an outer covering for earbud case, as shown and described.

DESCRIPTION

FIG. 1 is a front perspective view of an outer covering for earbud case according to a first embodiment of our design; FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of an outer covering for earbud case according to a second embodiment of our design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines of even length depict portions of the outer covering for earbud case that form no part of the claimed design.

1 Claim, 8 Drawing Sheets
